UNITED STATES PATENT OFFICE.

MILES M. JOHN, OF PEKIN, ILLINOIS.

GRAIN-CAR DOOR.

SPECIFICATION forming part of Letters Patent No. 792,829, dated June 20, 1905.

Application filed November 7, 1904. Serial No. 231,762.

To all whom it may concern:

Be it known that I, MILES M. JOHN, a citizen of the United States, residing at Pekin, in the county of Tazewell and State of Illinois, 5 have invented certain new and useful Improvements in Grain-Car Doors, of which the following is a specification.

This invention relates to car-doors of the type particularly designed for use as the inner side door of a grain-car in which grain is shipped in bulk or in loose form.

To this end the invention contemplates a simple and practical construction of door for grain-cars, which may be easily raised and lowered, so as to allow the grain to be removed from the car or to be placed therein in the most convenient manner without the usual difficulty attendant upon opening or raising the ordinary types of grain-car doors in common use. In this connection the invention has in view a novel mounting of the door which admits of the same being swung up to an out-of-the-way position beneath the roof of the car when it is desired to entirely uncover the door-opening through the side of the car either during the loading or unloading of the latter. Also the invention provides, in connection with the means for permitting the door to be swung to a substantially horizontal 25 position beneath the roof of the car and sustained in that position, a novel and practical means for guiding the door into its closed position over the door-opening and for securely retaining it in such position against displacement in any direction either laterally or vertically.

With these and other objects in view, which will more readily appear as the nature of the invention is better understood, the same consists in the novel construction, combination, and arrangement of parts, which will be hereinafter more fully described, illustrated, and claimed.

The essential features of the invention involved in carrying out the objects above indicated are necessarily susceptible to some structural change without departing from the spirit or scope thereof; but a preferred embodiment of the improvements is shown in the accompanying drawings, in which—

Figure 1 is an inner side elevation of one side of a grain-car, showing the same equipped with a door and door-mountings constructed in accordance with the present invention. Fig. 2 is a cross-sectional view of the grain-car, 55 showing the opposite doorways equipped with the improved door and door-mountings, the view illustrating one door with its extension raised and fastened and the other door with its extension lowered to partly uncover the 60 door-opening above the main door. Fig. 3 is a vertical sectional view at one side of the doorway, showing the door suspended in an inoperative position at the top of the car beneath the roof thereof. Fig. 4 is a front elevation of a grain-car door embodying the present improvements and showing the outside of the doorway portion of a grain-car to which it is fitted. Fig. 5 is a detail elevation showing the inner side portion of one of the door- 70 posts to illustrate the mounting of the fastening guides and guards for the door and the hinged extension thereof. Fig. 6 is a horizontal sectional view on the line 6-6 of Fig. 1, showing more plainly the fastening and guiding means for the door. 75

Like reference-numerals designate corresponding parts in the several figures of the drawings.

In carrying out the present invention the 80 improvements are associated with the usual doorway 1 of an ordinary type of grain or freight car 2 of the kind commonly employed for carrying grain in bulk or loose form. The doorways are usually provided in the 85 sides of the cars at opposite points, and each doorway is provided with the same equipment; but as the door equipment for both doorways is the same a description of one will suffice for the other.

The doorway 1 in the side of the car is of the usual dimensions and extends substantially the full height of the car-body. It is bounded at the opposite vertical sides thereof by the vertical side posts 3, and it is upon the 95 inner sides of these side door-posts that the improved grain-door is designed to be arranged and manipulated.

The grain-door proper is designated by the numeral 4 and is made of sheet metal, pref- 100

erably galvanized iron, being reinforced by a framework of iron strips or bars in the manner presently explained. This main door 4 is of the vertically sliding and swinging type, 5 inasmuch as it is designed to have a vertical sliding movement at the inner side of the doorway to provide the inside door for the latter and in addition to the vertical sliding movement is adapted to be swung up to a horizontal position beneath the roof of the car, as 10 will hereinafter more fully appear. The metal sheet constituting the body of the main sliding door has riveted or otherwise rigidly secured to the inner side thereof the upper 15 and lower supporting-bars 5 and 6, respectively, which extend across the full width of the door-plate and constitute a strong reinforcement for the top and bottom edges of the same. When the door is in its lowered 20 position, the lower bar 6 constitutes a bottom rest-sill which rests upon the floor of the car-body and resists outward strain imposed upon the bottom edge of the door by the weight of the material within the same.

25 Both the upper and lower supporting-bars 5 and 6 at the top and bottom edges of the door or door-plate 4 are provided with end hanger extensions 7 and 8, respectively. The end hanger extensions 7 from the supporting-bar 30 5 at the top edge of the door have loosely-arranged thereover carrying-links 9, which are loosely interlooped with sliding runner-rings 10, having a loose sliding engagement over the stationary guiding-rods 11, arranged 35 at opposite sides of the doorway 1 upon the inside of the car-body. The opposite guiding-rods 11 have vertical portions 12 extending parallel with the side of the car-body from a point at or about the plane of the top 40 edge of the main door 4 when the latter is lowered to a point at or about the plane of the top of the doorway 1, and from such point the guiding-rods 11 are formed with inwardly-curved roof-sections 13, extending beneath 45 the roof of the car-body to a point at or about the longitudinal center of the latter. This position of the guiding-rods 11 at opposite sides of the doorway 1 permits the top edge of the door 4 to be raised to the top of the 50 car upon the vertical portions 12 of the rods and then moved inward upon the roof-sections 13, whereby the door is brought to an approximately horizontal position and the end hanger extensions 8 of the lower supporting-bar 6 thereof are permitted to be lifted 55 into the stationary supporting-hangers 14, projected inwardly from the side of the car-body in a plane above the top of the doorway 1, as may be plainly seen from Fig. 3 of the 60 drawings. These stationary supporting-hangers 14 are preferably in the form of open hooks with upturned terminals.

The main sliding door 4 has riveted or otherwise rigidly secured to the outer side thereof 65 along its vertical edges the opposite parallel

slide-strips 16, provided with undercut or beveled portions 17, slidably interlocked with correspondingly beveled or undercut holding edges 18 of the stationary fastening-guides 19, secured to the inner sides of the opposite door-posts 3 contiguous to the longitudinal edges of such posts. The opposite slide-strips 16, carried by the main door 4, are spaced a greater distance apart than the stationary fastening-guides 19, so as to provide what may 70 be properly termed a "slidable dovetailed engagement" with said guides, as may be plainly seen from cross-sectional view, Fig. 6, of the drawings. This slidable dovetailed engagement of the slide-strips with the fastening-guides not only provides for definitely guiding the main door into a closed position over the lower portion of the doorway, but also constitutes a rigid fastening means for securely holding the door to the door-posts 75 against lateral or edgewise displacement.

To assist in the vertical guiding of the door, there are associated with the oppositely-arranged fastening-guides 19 the guard-strips 20, also secured to the inner sides of the door-posts 3 and arranged in longitudinal alinement with the guides 19. The guard-strips 20 terminate short of the top of the doorway and are of slightly less width than the guides 19, so that their outer edges will lie inside of 90 the plane of the undercut edges 17 of the guides, so as to permit the door 4 to become perfectly free from the said guides when lifted above the lower half of the doorway, while at the same time guided by the said 95 strips 20 in the continued upward movement for carrying the door into its elevated position upon the roof-sections 13 of the guiding-rods and the supporting-hangers 14. While 100 subserving these functions, the guard-strips 105 20 are specially designed to act as guards for the upper supplemental door extension 21, consisting of a metal sheet or plate hinged at one edge, as at 22, to the top edge of the main door 4, said hinges being so arranged as to 110 provide for the inward folding of the extension 21 back upon the inner side of the main door, as plainly shown in Fig. 2 of the drawings. The said upper supplemental door extension 21 has riveted or otherwise rigidly 115 fastened to the outer side thereof along its opposite vertical edges the short frame-strips 120 23, which engage along the outer edges of the guard-strips 20 to brace the extension against edgewise strain when in its extended position within the vertical plane of the main door 4.

The upper supplemental door extension 21 is provided along the upper and lower edges thereof with the upper and lower frame-bars 125 24 and 25, the upper bar 24 being preferably provided with the end extensions 26, adapted to be engaged by the fastening-latches 27, pivoted to the door-posts 3, as at 28. When 130 engaged with the said upper frame-bar of the

door extension, the latches not only serve to hold such extension in alinement with the main door, but also act as fastening means for holding down the entire door to secure the same against being jarred open. When it is desired to uncover the upper part of the door for any purpose, the latches 27 are released and the door extension 21 folded down upon the inner side of the main door. In this folded position the swinging edge of the door extension is engaged by the turn-button 29, carried by the main door. Also the folding extension is fastened in this manner when it is desired to lift the entire door and suspend it beneath the roof of the car in the manner already explained.

The main door or door plate 4 is provided therein near its bottom edge with an outlet-port 30, adapted to be covered and uncovered by an outwardly-opening relief-gate 31, hinged at its upper edge, as at 32, to the upper edge of the said port or opening 30. In its closed position the gate 31 covers or fills the port 30 and is held locked in such position by a locking-bar 33, pivoted intermediate its ends, as at 34, to the gate and having its opposite end portions engaging in the opposite reversely-disposed keepers 35, preferably arranged on or in the side posts or jambs of the doorway, as plainly shown in Fig. 4 of the drawings. A pivotal securing-button 36 is mounted upon the gate 31 and is designed to be turned against the bar 33 for holding the same in its keepers. By turning the button 36 away from the bar 33 and swinging the latter out of its keepers the gate 31 may be swung open to provide an outlet for the grain should it be desired to tap the same through said outlet, particularly for the purpose of relieving the outward pressure somewhat from the door before raising the same.

From the foregoing it is thought that the construction, operation, and many advantages of the herein-described grain-car door will be readily apparent without further description, and it will be understood that various changes in the form, proportion, and minor details of construction may be resorted to without departing from the spirit of the invention or sacrificing any of the advantages thereof.

Having thus described the invention, what is claimed, and desired to be secured by Letters Patent, is—

1. In a grain-car door, the combination with the car and its doorway, of stationary fastening-guides secured to the door-posts, guard-

strips extended above the fastening-guides in alinement therewith but having their outer edges lying inside the plane of the corresponding edges of said guides, a vertically-sliding main door carrying, at its vertical edges, strips which slidably interlock with the fastening-guides, a hinged door extension carried by the main door and provided with end frame-strips engaging the guard-strips, and means for guiding the door and its extension to an elevated position beneath the car-roof.

2. In a grain-car door, the combination with the car and its doorway, of a vertically-sliding main door having supporting-bars respectively at the top and bottom edges thereof, fastening-guides for said main door a supplemental door extension hinged to the top edge of the door and having at its upper edge a frame-bar provided with end extensions, guard-strips co-operating with said hinged door extension fastening-latches mounted on the car-body and engaging the end extensions of said frame-bar of the door extension when the latter is in its closed position, stationary guiding-rods arranged at opposite sides of the doorway and having inwardly-extending sections located beneath the car-roof, a slide connection between said guiding-rods and the upper supporting-bar of the main door, and stationary hangers carried by the car-body above the doorway and adapted to receive the ends of the lower supporting-bar of the main door when guided to an approximately horizontal position beneath the roof.

3. In a grain-car door, the combination with the car and its doorway, of stationary fastening-guides secured to the door-posts and provided with undercut outer holding edges, guard-strips extended above the fastening-guides in alinement therewith, a vertically-sliding main door carrying, at its vertical edges, sliding strips provided with undercut edges slidably interlocking with the corresponding edges of said fastening-guides, a hinged door extension carried by the main door and provided with end frame-strips engaging at the sides of the guard-strips, and means for guiding the door and its extension to an elevated position beneath the car-roof and for suspending it in such position.

In testimony whereof I affix my signature in presence of two witnesses.

MILES M. JOHN.
